UNITED STATES PATENT OFFICE.

HERMANN F. SCHELLING, OF WEEHAWKEN, NEW JERSEY.

LATHERING APPARATUS.

No. 834,760.

Specification of Letters Patent.

Patented Oct. 30, 1906.

Application filed October 17, 1905. Serial No. 283,180.

To all whom it may concern:

Be it known that I, HERMANN F. SCHELLING, a citizen of the United States, residing at Weehawken, in the county of Hudson and 5 State of New Jersey, have invented new and useful Improvements in Lathering Apparatus, of which the following is a specification.

In barber-shops the lather is frequently rubbed by the barbers by hand onto the faces 10 of the customers.

This apparatus is to rub or distribute the lather over the face mechanically.

This invention is set forth in the following specification and claims and illustrated in 15 the annexed drawings, in which—

Figure 1 is an elevation of a shaft with a tip or terminal embodying this invention. Fig. 2 is a section of Fig. 1. Fig. 3 is an edge view of the stem of a tip or terminal. Fig. 4 20 shows the manner of mounting or suspending a shaft.

The apparatus comprises the usual flexible rotary shaft used in the drills or machines of dentists. This flexible rotary or oscillating 25 shaft is shown at *a* and is provided with the usual clamp or connecting means *b* for detachably engaging a tool.

The tip or terminal *c* for distributing the lather over the face, as shown, is a piece of 30 horn or suitable material tapered and fluted.

The soap or lather is applied as usual to the face by a brush. The tip or distributor *c* while rotating or oscillating is then passed over the face and has the effect of beating 35 and rubbing the lather over the skin and also

of softening the beard, and the hand of the barber need not be employed for this purpose. This tip being suitably fluted or channeled will cause the formation of foam or the distribution of lather. The fluted or channeled 40 surface need not be of the exact configuration shown, as its shape can be varied without interfering with its utility for the purpose intended.

The shaft *a* can be suspended from a suitable motor, electric or other kind, Fig. 4, or mounted in any suitable way.

A handle or bail *d* can be applied to the device for convenient manipulation, but is not necessary.

What I claim as my invention, and desire to secure by Letters Patent, is—

1. A lathering device comprising a rotatable member, a handle therefor, and a tapering terminal provided with longitudinally-extending channels, said terminal connected to and rotating with said member.

2. A lathering device comprising a rotatable member, and a terminal provided with longitudinally-extending channels, said terminals connected to and rotating with said member.

In testimony whereof I have hereunto set my hand in the presence of two subscribing witnesses.

HERMANN F. SCHELLING.
